DESIGN FOR A FINGER RING

Margarita Mercedes Maguin, New York, N. Y.

Application October 16, 1940, Serial No. 95,870

Term of patent 7 years

To all whom it may concern:

Be it known that I, Margarita Mercedes Maguin, a citizen of Colombia and resident of New York, in the county and State of New York, have invented a new, original, and ornamental Design for a Finger Ring, of which the following is a specification, reference being had to the accompanying drawing, forming part thereof.

The figure represents a perspective view of a finger ring embodying my new design.

I claim:

The ornamental design for a finger ring, substantially as shown.

MARGARITA M. MAGUIN.
